US00D770380S

(12) **United States Design Patent** (10) **Patent No.:** **US D770,380 S**
(45) **Date of Patent:** **** Nov. 1, 2016**

(54) **RECHARGEABLE BATTERY DEVICE**

- (71) Applicant: **Limefuel, LLC**, Boulder, CO (US)
(72) Inventor: **Paul Lin**, Boulder, CO (US)
(73) Assignee: **Limefuel, LLC**, Boulder, CO (US)
(**) Term: **15 Years**
(21) Appl. No.: **29/548,458**
(22) Filed: **Dec. 14, 2015**

(57) CLAIM

The ornamental design for a rechargeable battery device, as shown and described.

DESCRIPTION

FIG. 1 is a front perspective view of the rechargeable battery device;

FIG. 2 is a rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines showing a rechargeable battery device are included for the purpose of illustrating environment and form no part of the claimed design.

1 Claim, 4 Drawing Sheets
